DESIGN FOR A TOILET ACCESSORY BOTTLE

Eugene J. Lux, New York, N. Y., assignor to Harriet Hubbard Ayer, Inc., New York, N. Y., a corporation of New York

Application August 14, 1937, Serial No. 71,081

Term of patent 3½ years

To all whom it may concern:

Be it known that I, Eugene J. Lux, a citizen of the United States of America, residing at New York city, in the county of New York, Borough of Manhattan, and State of New York, have invented a new, original, and ornamental Design for a Toilet Accessory Bottle, of which the following is a specification, reference being had to the accompanying drawing, forming a part thereof, in which

I claim:

The ornamental design for a toilet accessory bottle, as shown.

EUGENE J. LUX.
